UNITED STATES PATENT OFFICE.

JOHN H. WHITE, OF NORTH YAKIMA, WASHINGTON.

DIMMER FOR HEADLIGHTS.

1,272,746.

Specification of Letters Patent. Patented July 16, 1918.

Application filed August 23, 1917. Serial No. 187,815.

To all whom it may concern:

Be it known that I, JOHN H. WHITE, a citizen of the United States, residing at North Yakima, in the county of Yakima,

5 State of Washington, have invented certain new and useful Improvements in Dimmers for Headlights; and I do hereby declare the following to be a full, clear, and exact description of the invention, such as will enable others skilled in the art to which it appertains to make and use the same.

This invention is an improvement in headlights and has particular reference to a dimmer therefor.

10 Another object is to provide an improved covering for the reflector of a vehicle headlight whereby the blinding glare therefrom is obviated, thus reducing the danger to pedestrians and passing vehicles.

15 Another object is to provide a dimmer of this character which is simple in construction, easy to manufacture and effective in carrying out the purpose for which it is designed.

20 Another object is to provide a dimmer which may be quickly applied or removed and which will require no special fastening devices nor any modification in the headlight structure.

25 The inventive idea involved is capable of receiving a variety of mechanical expressions, one of which, for the purpose of illustrating the invention, is shown in the accompanying drawing, wherein:

30 Figure 1 is a front elevation of the headlight showing a dimmer applied thereto and constructed in accordance with the invention.

35 Fig. 2 is a longitudinal sectional view through the headlight.

In the drawing the numeral 5 indicates a headlight which may be of any preferred construction since a particular type of headlight forms no part of the present invention.

40 The headlight is provided with the usual reflector 6 in the rear portion of the centrally mounted incandescent lamp 7.

45 The dimmer which comprises the essential feature of the invention preferably consists of a covering 8 for the reflector made

of a wire mesh fabric bent to conform to the contour and engage the surface of the reflector and provided centrally thereof with an opening 9 for receiving the socket of the lamp 7. With this form of covering, the rays of light from the lamp 7 striking a reflector are diffused to a certain extent by the wire fabric so as to reduce the flare in front of the vehicle.

50 It is further proposed, however, to cause an additional diffusion of the rays of light which strike the lower portion of the reflector and pass upwardly from the same since these reflected rays are the ones which are mainly instrumental in producing the glare in the eyes of persons in front of the machine or vehicle, the rays of light which are cast downwardly by the upper portion of the reflector being thrown upon the ground. In order to accomplish this additional diffusion of the rays of light from the lower portion of the reflector, use is preferably made of a piece of cloth fabric or gauze of finer mesh than the wire fabric sewed or otherwise secured to the wire fabric 8, the 55 cloth fabric 10 being of a size sufficient to cover the lower portion of said cover or fabric 8 and having its upper edge extending slightly above the opening 9. It will be apparent from the foregoing description that 60 rays of light from the lamp 7 will be diffused to a certain extent by the upper portion of the covering 8 and will be further diffused by the double thickness of wire and cloth fabric forming the lower portion of 65 the dimmer thus obviating the glare usually incident to vehicle headlights.

65 The opening 9, while receiving the lamp socket, is smaller than the diameter of the lamp bulb, and thus the bulb serves to hold 70 the dimmer against disengagement from the socket. No additional fastening means is necessary, since the native stiffness of the wire fabric will hold it in conformity to the surface of the reflector.

75 What is claimed is:

1. In a headlight, the combination with a reflector; of a covering therefor consisting of wire fabric bent to conform to the contour of and engaging the reflector and hav- 80

ing a lamp opening therein, and a cloth fabric secured to said wire fabric and covering substantially the lower half thereof.

2. In a headlight, the combination with a reflector; of a covering therefor consisting of wire fabric bent to conform to the contour of and engaging the reflector and having a lamp opening therein, and a cloth fabric secured to said wire fabric and covering

the lower portion thereof, the upper edge of 10 said cloth fabric extending above said lamp opening.

In testimony whereof, I affix my signature in the presence of two witnesses.

JOHN H. WHITE.
